(57) **CLAIM**

The ornamental design for a display screen or portion thereof with graphical user interface, as shown and described.

DESCRIPTION

FIG. 1 is a front view of an electronic device with a display screen showing the claimed design;

FIG. 2 is a rear view thereof.

FIG. 3 is a left side view thereof.

FIG. 4 is a right side view thereof.

FIG. 5 is a top view thereof; and,

FIG. 6 is a bottom view of the thereof.

The inner dash-dot-dash broken-line rectangle in FIG. 1 shows the perimeter of a display screen and forms no part of the claimed design. The remaining dash-dot-dash broken lines in the figures show portions of an electronic device and form no part of the claimed design.

The dash-dash broken lines in FIG. 1 illustrate portions of a graphical user interface and form no part of the claimed design.

1 Claim, 6 Drawing Sheets
